TOY ELEPHANT FIGURE

Lynn Benner Northrop, Strykersville, N.Y., assignor to
The Quaker Oats Company, Chicago, Ill.

Filed Jan. 2, 1974, Ser. No. 430,022

Term of patent 14 years

Int. Cl. D21—01

U.S. Cl. D34—2 R

FIG. 1

FIG. 1 is a side elevational view of a toy elephant figure showing my new design;

FIG. 2 is a front view thereof; and
FIG. 3 is a rear view thereof.

I claim:

The ornamental design for a toy elephant figure, substantially as shown and described.
